UNITED STATES PATENT OFFICE.

THEODORE A. GEY, OF NORRISTOWN, PENNSYLVANIA.

BOTTLE-STOPPER.

1,104,418.

Specification of Letters Patent. Patented July 21, 1914.

Application filed October 23, 1913. Serial No. 796,905.

To all whom it may concern:

Be it known that I, THEODORE A. GEY, citizen of the United States, residing at Norristown, Pennsylvania, have invented certain new and useful Improvements in Bottle-Stoppers, of which the following is a specification.

My invention is designed to provide an inexpensive and efficient form of bottle stopper, and is applicable more particularly to bottles which are provided with spiller or drip tubes. I aim to avoid the use of screw cap closures, and to provide a cap which will have a double closing effect at two points, and one which may be readily thrust or pressed into place and as readily removed.

The invention is shown in the accompanying drawings, in which:

Figure 1 is a sectional view of the upper portion of a bottle or container with the invention in place; Fig. 2 is a sectional view of the cap or closure member; Fig. 3 is a view of the cork which fits in the neck of the bottle and receive the spiller tube which is preferably made of glass and the closure member. Fig. 4 is a detail of another embodiment of my invention.

In these drawings, 1 is the bottle neck in which is inserted a cork 2 carrying a spiller tube 3 which projects beyond the cork and the mouth of the bottle. The spiller tube is held in the cork by its frictional contact therewith, which frictional contact is augmented by the pressure of the cork thereon due to forcing it into the bottle mouth under some compression, the cork being of a diameter to make a tight fit in the bottle mouth. At a point about midway of the height of the cork, the diameter of the opening therethrough is slightly enlarged to receive a depending tubular portion 4 of the cap or closure 5. This cap or closure 5 may be of any ornamental construction consisting of the upper main portion or handle 6 and a laterally extending portion 7 to overlie the cork and the bottle lip. The main portion 6 of the closure has a washer of cork or other material therein, as shown at 8, and when the closure is in place this washer forms a seat for the upper end of the spiller tube which fits closely within the bore of the closure and the washer serves to make a fluid tight joint at this point. The depending tubular portion of the closure also fits closely the exterior of the

spiller tube, and between this and the wall of the enlarged central bore in the cork. The cork presses on the outer side of this depending tubular portion of the closure member, and this depending portion also fits a seat on the shoulder 9 of the cork. The compression of the cork due to inserting it in the bottle mouth of slightly smaller diameter will not only tend to hold the spiller tube firmly in place, but will also contract or reduce the diameter of the enlarged opening sufficiently to cause the cork to press firmly upon the outer side of the depending tubular portion of the cap, serving not only to hold the cap firmly in place against accidental removal or loss, but also to form a fluid tight joint at this point. I prefer to make the cap with all its parts of one piece.

In Fig. 4 I show a form of the invention in which it is not necessary to provide the cork with an enlargement at the upper end of its passage. In this form of the invention I employ a straight cork or one of cylindrical form externally, and of such size in relation to the bottle mouth that when it is placed in position, as shown in Fig. 4, it will be compressed at its lower end to securely grip the glass tube, it being understood, of course, that the glass tube is gripped sufficiently tight to prevent its displacement at all times whether the stopper be in or out of the bottle mouth. The stopper, however, when so placed, as shown in Fig. 4, will have its upper portion sufficiently free from compression by the wall of the bottle mouth as to permit the insertion or introduction of the tubular extension 4 of the cap or closure 5 between said cork and the outer surface of the glass tube. In other words, there will be sufficient looseness at the upper end of the cork to permit the insertion of the part 4. When inserted, this part will be gripped by the cork and held sufficiently tight to make a liquid tight joint. In this form, the packing 8 may be omitted. I prefer to use a small glass tube having its bore of such diameter as will prevent accidental spilling should the bottle be laid on its side, the glass tube presenting the necessary capillary attraction for this purpose.

I claim as my invention:—

A stopper consisting of a cork of substantially cylindrical exterior with a glass spiller

tube projecting above the cork and a closure having a portion to fit over the glass tube and a downward tubular extension to fit between the upper portion of the cork and the glass tube, said cork being adapted for insertion in a tapered mouth bottle to thereby compress the lower end of the cork and leave the upper end free for the insertion

of the tubular extension of the closure, substantially as described.

In testimony whereof, I affix my signature in presence of two witnesses.

THEODORE A. GEY.
